DRY KILN

Filed Sept. 7, 1927

Inventor:
Malcolm B. Hall,
By Emery Booth, family Name
Attest,

UNITED STATES PATENT OFFICE

MALCOLM B. HALL, OF FOXBORO, MASSACHUSETTS, ASSIGNOR TO THE FOXBORO COMPANY, OF FOXBORO, MASSACHUSETTS, A CORPORATION OF MASSACHUSETTS

DRY KILN

Application filed September 7, 1927. Serial No. 217,977.

This invention relates to dry kilns and the object is to provide improved means for manifesting the temperature and humidity conditions therein to permit desired observation or control of the drying process. My invention will be well understood from the following description taken in connection with the accompanying drawings, wherein I have shown diagrammatically, partly in longitudinal section with parts broken away, a lumber kiln with which is associated an automatic humidity controlling mechanism exemplifying the principles of my invention.

Referring to the drawings, I have there illustrated in diagrammatic section a kiln 3 in which are disposed the trucks 5 carrying lumber to be dried. The humidity conditions in the kiln may be suitably controlled, herein by the joint action of the heating means, such as steam pipes 7, and moisture-supplying means, such as the spray pipe 9.

Theoretically and desirably the condition of the air circulating in a kiln of this character should be uniform throughout. However, because there may be a space between the several trucks on which the lumber is piled, or because of uneven stacking on the trucks themselves or non-uniformity of the material being dried, the conditions at different points of the kiln may considerably vary. The object of the present invention is to provide for controlling the humidity conditions in response to the conditions in some part of the kiln in which one of the controlling factors is at a maximum wherever this part of the kiln may be located, and thus to insure that no portion of the charge shall be subjected to conditions which would be detrimental to its proper drying.

By way of example I have herein shown in a very diagrammatic form suitable automatic controlling means, embodying suitable servomotors 11 and 13 respectively controlling admission valves in the steam line leading to the heater 7 and the spray pipe 9. These may be pneumatically operated through the action of control heads 15 and 15^a each governed by a suitable control couple which, as in the case of head 15, may embody a nozzle member 17 having an ex-

haust port and a valve seat and a cooperating valve 19. The construction of this controlling mechanism is shown herein in a diagrammatic manner only and may in practice be substantially as shown in the patent to 55 Dixon 1,582,868, dated April 27, 1926. The valve seat member 17 may be adjusted, conveniently manually, and the cooperating valve 19 may be automatically moved in relation thereto by means of a suitable thermometric responsive element 21 which may be a helical tube of the type shown in the patent to Bristol 1,195,334, dated August 22, 1916, adapted to be distorted by vapor pressure internally thereof to operate the valve 19. 60

For controlling the spray pipe 9 the helical tube 21^a may be connected by means of a fine-gage or capillary transmission tube 23 with a wet bulb device inside the kiln comprising 70 a suitable bulb or liquid-containing reservoir 25 which has applied thereto the textile cover 27 dipping into a water reservoir 29 or some equivalent device. The tube 21^a thus responds to the wet bulb temperature in well known manner. The tube 21, which is designed to operate in accordance with the dry bulb temperature within the kiln, may be connected with the interior of the kiln by a similar capillary transmission tube 31 but instead of utilizing an enlarged liquid-containing bulb within the kiln this fine-gage tube is extended at 33 throughout the length of the kiln and exposed to the temperature conditions therein. The total volume of the capillary tube is not substantially in excess 80 of that of the ordinary bulb and it in itself constitutes the bulb by means of which the dry bulb temperature, so-called, is rendered effective to operate the tube 21.

By the means described the element 21 and 90 consequently the action of the servomotor 11 which is governed thereby depends upon the maximum temperature in the kiln in whatever zone the maximum may occur. By "maximum temperature" in the instance illustrated is to be understood the maximum temperature of the air at any given zone longitudinally of the kiln at the location of the capillary bulb 33. It will be understood that the pipe 33 being full of vaporizable liquid, 95 100

heat applied at a certain zone thereof will vaporize the same causing a pressure which is the function of the temperature. This pressure acting on the liquid in zones of less heat will retain the liquid in these parts as liquid. That is, in these zones the liquid cannot boil. A pressure corresponding to the maximum temperature is thus transmitted to the helical tube 21 and governs the operation of the control couple 17—19 and thus through the control head 15, servomotor 11 and the heating device 7.

It will be understood that, while I have herein shown the conditions in the kiln as automatically controlled by the action of the wet and dry bulbs, these might operate indicating or recording instruments manifesting the conditions in the kiln and that control, if necessary, might be effected manually in accordance with the readings of such instruments. If the controlling instruments are of the type disclosed in the Dixon patent referred to, obviously they also serve to record and indicate the values of the variables.

I have described in detail the illustrated diagrammatic disclosure of a certain embodiment of my invention in order that the principles underlying the same might be well understood. Obviously the mechanism utilized may be considerably varied from what is shown and what I claim as new and desire to secure by Letters Patent I shall express in the following claim.

Claim:

A dry kiln having means for manifesting humidity conditions therein comprising pressure-operated elements adapted to respond to the wet and dry bulb temperature respectively and including a fine-gage tube filled with liquid which vaporizes within the range of temperature which the kiln has in use and extending substantially throughout the length of the interior of the kiln and in communication with the second of said elements and constituting in itself the source of actuating pressure therefor.

In testimony whereof, I have signed my name to this specification.

MALCOLM B. HALL.
